CLAIM

The ornamental design for a phone body, as shown and described.

DESCRIPTION

FIG. 1 is a front-top perspective view of a phone body showing my new design;

FIG. 2 is a front-bottom perspective view thereof;

FIG. 3 is a rear-top perspective view thereof;

FIG. 4 is a front elevational view thereof;

FIG. 5 is a rear elevational view thereof;

FIG. 6 is a left elevational view thereof, where the right elevational view is mirrored thereto;

FIG. 7 is a top plan view thereof; and,

FIG. 8 is a bottom plan view thereof.

The broken lines in the drawings illustrate portions of the phone body which form no part of the claimed design.
